UNITED STATES PATENT OFFICE

ALLAN S. BARROWS, OF LOS ANGELES, CALIFORNIA, ASSIGNOR TO THE YOUNGSTOWN STEEL DOOR COMPANY, OF CLEVELAND, OHIO, A CORPORATION OF OHIO

DUMP DOOR FOR RAILWAY CARS

Application filed August 7, 1925. Serial No. 48,816.

This invention relates to dump doors for railway cars.

An object of the invention is to provide an improved form of door for hopper, dump, and general service cars which will be strong and economical of manufacture, and which includes a plurality of metallic sheets, rigidly fastened together, the upper sheet, or the sheet upon which the material is adapted to rest, preferably being of smooth high grade carbon steel alloy so as to resist abrasion, and the other of said sheets being of thinner gage and secured to the main door sheet, the second sheet being of lower grade material and provided with certain integral reinforcing means arranged so as to brace the door in a simple and effective manner.

Other and further objects of the invention will more fully and clearly appear from the description and claims hereinafter following.

In the drawings Figure 1 is a bottom plan view of a door constructed in accordance with my invention, and adapted to be used with a hopper construction; Figure 2 is a transverse sectional view of the invention on the line 2—2 of Figure 1; Figure 3 is a vertical longitudinal sectional view through the hopper portion of a car of the ordinary hopper type, showing a door constructed in accordance with the principles of the present invention applied thereto; Figure 4 is an enlarged fragmentary vertical sectional view of the invention similar to Figure 2, showing a slightly different embodiment of the invention; and Figure 5 is a fragmentary vertical sectional view of the invention arranged for use in connection with a dump, or general service car.

Referring first to Figure 3 of the drawings, the hopper side of the car is indicated at 5, and 6 designates the corresponding hopper floor plate. A transverse connecting plate is indicated at 7 and pivotally secured to such plate by hinge brackets indicated at 8, are hinge straps shown at 9, adapted to be fas-

tened to the car door, this construction being of a well known type.

The door 10 is adapted to close the opening of the hopper defined by the various component parts of the hopper section. Said door comprises a main door sheet 11, which is preferably in the form of a comparatively thin plate of high carbon steel alloy, which has properties of successfully resisting abrasion, occurring in actual practice, due to the sliding of the material on the door plate when the door is opened. The side and forward margins of the main sheet 11 are provided with upturned flanges 12 and 13, the flanges being integrally formed with the door sheet and with each other, and a rear flange 13a is provided which is turned in the opposite direction, having cut out portions 14 which are provided to permit extension of the hinge straps 9 therethrough in order to fasten the same to the door, said flanges serving to brace the main door sheet.

Secured to the undersurface of the door sheet 11 is a reinforcing door sheet 15, preferably of thinner gage than the door sheet 11, and of a cheaper grade of material, the sheet 15 being slightly smaller in final form than the main door sheet 11, and the body portions of the two sheets are rigidly secured together by suitable means such as rivets 20, which are counter-sunk in the main sheet 11, to preserve the smooth unobstructed top surface thereof. The two sheets 11 and 15 may be secured together by spot welding if desired, instead of utilizing rivets for this purpose.

The sheet 15 is provided with an arrangement of corrugations which are for the purpose of lending strength to the reinforcing sheet 15, which in turn braces the main door sheet 11. Said corrugations preferably include one of rectangular formation, the side portions 21 and 22 of which extend in substantial parallelism with the longitudinally extending margins of the door sheets, and

transverse portions 23 which connect the longitudinal portions 21 and 22 at their ends, the portion 22 of the corrugation preferably being disposed a greater distance from the front edge of the door sheet, than the portion 21 of the corrugation is spaced from the rear longitudinal edge of the door sheet, for the purpose of providing a flat section 25 free of corrugations, to which may be attached suitable securing brackets (not shown), of various ordinary and usual construction. Formed in the sheet 15 so as to merge with the portions 21 and 22 of the rectangular corrugation, is a plurality of spaced transversely extending corrugations 26, said corrugations being arranged so as to merge with the portions 21 and 22 so as to provide an arrangement of connected corrugations, which may be formed at one time and which 20 brace the door in all directions.

The connecting end corrugations 23 are each spaced a suitable distance from the transverse edge of the door sheet 15, and between the edges of the door 15, and the end 25 corrugations at each side of the door member is formed a transversely extending corrugation 27, which braces the transverse edge of the door, and due to the spacing thereof allows room for the projection of the hinge 30 straps 9 an appreciable distance inwardly of the edge of the door, said hinge straps extending along the door sheet 15, between said corrugations, and being fastened in position by suitable rivets 28.

By this arrangement the main door sheet 11 may be made up of a relatively thin sheet of high carbon steel alloy so as to resist abrasion and present a smooth unobstructed surface to the flow of the material when the same 40 is dumped from the car, and this comparatively thin sheet of material may be adequately braced by an auxiliary sheet of relatively low grade material, the reinforcing sheet being braced by the corrugations to compensate 45 for stresses tending to distort the door in a longitudinal direction, and against distortion transversely, the corrugations being arranged in a novel manner so as to merge, permitting the corrugations to be formed at 50 one operation, and providing an arrangement of exceptional strength. It will be appreciated that the flanges 12 and 13, of the main sheet may be formed to extend in a direction opposite to that shown as indicated in Figure 5, if it is desired to use this type of door in a 55 hopper arrangement.

A slightly different embodiment of the invention is illustrated in Figure 4 of the drawing, this construction including a main sheet 60 30, and an auxilliary sheet 31, rigidly connected together by suitable rivets or spot welding, the sheet 31 being provided with corrugations which serve to brace the door structure, such door structure being identically similar to that hereinbefore described

except for the fact that the flanges 12 and 13 upon the sheet 11, are omitted therefrom, and a somewhat different means associated with the door structure for bracing the side edges thereof. Said means include an angle member 34 extending along each transverse edge of the door member, the flange 35 of such bar being disposed flatwise upon the undersurface of the sheet 31, and the flange 36 of such bar being disposed at right angles thereto, and extending along the edges of both door sheets 30 and 31, and projecting beyond the upper surface of the sheet 30, the rivets 37 for securing the flange 35 to the door structure preferably extending through both door sheets 30 and 31 as shown, the rivet heads on the upper side of the sheet 30 being countersunk to preserve the smooth unobstructed surface of the door structure. Although only one side edge of the door structure is illustrated in the drawing, it of course will be understood that the opposite side edge of the door structure and the forward edge of the same is provided with a similar angle bar in the same manner as above described with reference to the angle bar 34.

When the door is intended to be used as a side or floor door in dump or general service cars, the construction may be slightly varied in the manner illustrated in Figure 5. Referring to said figure, the two sheets 50 and 51 are formed and secured together in the same manner hereinbefore referred to, the main sheet 50 being provided with an integral flange 52 turned in the direction of the sheet 51, only one side edge of the door being shown in Figure 5, but it will be understood that the other side edge, as well as the front and rear edges are provided with similar flanges. Each of the edges of the door may be reinforced by an angle member 53, one flange of which is secured to the undersurface of the sheet 51, and the other flange of which is secured to the flange 52 of the sheet 50. When the construction is used as a floor or side door, it will present the smooth surface toward the material in the car, the reinforcing edge members projecting outwardly therefrom.

While I have herein shown and described what I now consider the preferred manner of carrying out my invention, the same is merely illustrative and I contemplate all changes and modifications that come within the scope of the claims appended hereto.

I claim:

1. As an article of manufacture, a dump door comprising a plurality of sheets rigidly secured together, one of said sheets being of hardened wear resisting steel and the other of said sheets being of lower grade material and including integral reinforcing means for strengthening said first sheet.

2. As an article of manufacture, a dump door including a plurality of door sheets rig-

5 idly secured together, one of said sheets being provided with a smooth unobstructed surface adapted to be disposed in contact with the material associated therewith, and the other of said sheets being substantially 10 co-extensive with said first sheet and provided with a plurality of integral corrugations for bracing the door sheets, said corrugations including a plurality of portions extending at an angle to each other and merging to provide a continuous corrugation.

15 3. As an article of manufacture, a car door including a plurality of door sheets rigidly secured together, one of said sheets being provided with a smooth unobstructed surface 20 adapted to be disposed in contact with the material associated therewith, and the other of said sheets being provided with a plurality of corrugations for bracing the door sheets, certain of said corrugations extending adjacent the longitudinal edges of the door sheet, and other of said corrugations extending transversely of said door sheet.

25 4. As an article of manufacture, a dump door including a plurality of door sheets rigidly secured together, one of said sheets being provided with a smooth unobstructed surface adapted to be disposed in contact with the material associated therewith, and the other of said sheets being provided with a plurality of corrugations for bracing the door sheets, certain of said corrugations extending adjacent the longitudinal edges of the door sheet, and other of said corrugations extending transversely of said door sheet, and merging with said longitudinally extending corrugations to provide a continuous arrangement.

30 5. In a door of the character described, the combination with a door sheet having a smooth unobstructed surface adapted to be disposed in contact with the material carried thereby; and a reinforcing door sheet rigidly secured to said first sheet and having formed therein reinforcing corrugations, a plurality of which extend transversely of said door sheet, and others of which extend longitudinally of said door sheet, certain of said transverse corrugations merging with 35 said longitudinal corrugations, and others being spaced therefrom; and hinge straps fastened to the door sheets and extending within the spaces between certain of said transversely disposed corrugations.

40 6. As an article of manufacture, a main dump door comprising a metallic sheet formed of wear resisting material, and being provided with flanges along its edges extending at an angle to the main body of the sheet, and a sheet of material substantially co-extensive with said main door sheet integral- 45 ly reinforced and rigidly secured to said main door sheet.

45 7. As an article of manufacture, a main door sheet formed of wear resisting material,

and being provided with flanges along its edges extending at an angle to the main body of the sheet, and a corrugated sheet of material rigidly secured to said main sheet, said second sheet having angular flange portions 50 associated therewith and rigidly secured to the flanges of said first sheet.

8. As an article of manufacture, a main door sheet formed of wear resisting material, and a sheet of material substantially co-extensive with said main door sheet and integrally reinforced and rigidly secured to said main sheet; and means on said door for reinforcing the edges of said door, said means being in the form of angular members rigidly secured to the door edges.

15 9. A dump door for the discharge opening of a railway car, the same being formed of a sheet of metal conforming in general shape to the outline of the discharge opening, said sheet having a smooth unobstructed upper surface; of a second sheet rigidly secured to the undersurface of said first sheet, said second sheet being provided with a plurality of corrugations extending at an angle to each other to brace said door sheets.

20 10. In a device of the character described, the combination with a hopper section defining a hopper opening; of a pivoted door for closing said opening, said door comprising an upper door sheet of hardened wear resisting material; a second sheet rigidly connected to said first sheet and provided with a plurality of integral reinforcing elements and arranged to brace the door sheets; and angularly disposed reinforcing elements associated with the edges of said door.

25 11. A dump door comprising a main door sheet formed of metallic wear resisting material, and an integral reinforced metallic sheet substantially of the same size as said main sheet and rigidly secured to said main sheet, and adapted to brace the same; and means on said door for reinforcing the side edges thereof.

30 12. As an article of manufacture, a door including: two metallic sheets, one having integrally formed strengthening indentations incorporated therein, said two sheets being rigidly secured together in face-to-face relation, whereby one sheet is reinforced per se and the two sheets mutually co-act to reinforce and brace each other against deformation, said door having flanges along some 35 of the edges thereof.

35 13. As an article of manufacture, a pivoted dump door for cars, said door including: a flat metallic sheet and a second metallic sheet having integrally formed strengthening indentations incorporated therein, said two sheets being rigidly secured together and in surface-to-surface contact throughout the area of said indented sheet, except where the latter is indented, whereby the indented sheet 40 is integrally reinforced and the two sheets

mutually co-act to reinforce and brace each other against bending, said door having a flanged formation along some of the edges thereof.

5 14. In combination with the other elements of a railway dump car, a plate metal door having an embossed panel pressed from the plane of the plate with flat margins surrounding said panel, and a metallic sheet secured to said plate.

10 In witness that I claim the foregoing I have hereunto subscribed my name this 28th day of July, 1925.
